(57) **CLAIM**

The ornamental design for an aerosol actuator for an aerosol device, as shown and described.

DESCRIPTION

FIG. 1 is a perspective view of an aerosol actuator for an aerosol device showing the new design;

FIG. 2 is a front view of the new design;

FIG. 3 is a back view of the new design;

FIG. 4 is a right view of the new design;

FIG. 5 is a left view of the new design;

FIG. 6 is a top view of the new design; and,

FIG. 7 is a bottom view of the new design.

The broken-line disclosure is understood to represent unclaimed portions of the article in which the claimed design is embodied.

1 Claim, 4 Drawing Sheets

FIG. 1

FIG. 2

FIG. 3

FIG. 4**FIG. 5**

FIG. 6
